Primary Examiner — Patricia Palasik(74) *Attorney, Agent, or Firm* — Workman Nydegger(57) **CLAIM**

The ornamental design for an outfeed table, as shown and described.

DESCRIPTION

FIG. 1 is a perspective view of an outfeed table showing our new design;

FIG. 2 is a front side elevational view of the outfeed table, as shown in FIG. 1;

FIG. 3 is a back side elevational view of the outfeed table, as shown in FIG. 1;

FIG. 4 is a right side elevational view of the outfeed table, as shown in FIG. 1;

FIG. 5 is a left side elevational view of the outfeed table, as shown in FIG. 1;

FIG. 6 is a top plan view of the outfeed table, as shown in FIG. 1; and,

FIG. 7 is a bottom plan view of the outfeed table, as shown in FIG. 1.

The broken lines shown in the figures are for illustrative purposes only and form no part of the claimed design. The broken lines in the drawings depict unclaimed environmental subject matter.
